LAPPING APPARATUS

Reinhold Stoll, Elgin, Ill., assignor to Western
Electric Company, Incorporated, New York,
N. Y., a corporation of New York

Application August 25, 1944, Serial No. 551,188

11 Claims. (Cl. 51—119)

1

This invention relates to a lapping apparatus and more particularly to an apparatus for lapsing thin parts, such as feeler gages.

In lapsing parts like feeler gages, difficulty has been experienced in securing flat and parallel faces on said parts when they are not perfectly flat before lapsing. A curved or bowed part may be lapped to a desired thickness, but, when removed from the lapsing machine, may resume its bowed shape, which may nullify its usefulness.

An object of the present invention is to provide an effective lapsing device for accurately lapsing parts.

In accordance with one embodiment of the invention, there is provided a stationary lower lapsing member and a movable upper lapsing member resting thereupon and spaced therefrom by a plurality of adjustable supports capable of being worn away and supporting the upper lapsing member to prevent undue pressure on a part to be lapsing in the initial stages of the lapsing operation, the supports wearing away as the lapsing of the part proceeds.

The invention will be more fully understood from the following description taken in conjunction with the accompanying drawing illustrating one embodiment thereof, in which

Fig. 1 is a perspective view of the lapsing apparatus;

Fig. 2 is a vertical cross section of the lapsing apparatus taken on the line 2—2 of Fig. 1; and

Fig. 3 is a bottom plan view of the upper lapsing member.

Referring to the drawing, there is shown a lower stationary lapsing member 10 having a flat lapsing surface 11 provided with parallel longitudinal and transverse scoring 12. An upper lapsing member 14 is rectangular in shape and of substantial thickness to provide a weight sufficient to exert the necessary downward force during the lapsing operation. The lapsing member 14 has a flat lapsing surface 15 provided with parallel longitudinal and lateral scoring 16 therein. A plurality of threaded apertures 17 are provided in the upper lapsing member, one adjacent each corner thereof, the lower ends of which are enlarged, as at 18, to receive cylindrical supporting members or studs 20 of equal hardness. The studs 20 tightly engage the walls of the apertures 18 and are adjustable therein and held in adjusted position by adjusting screws 21 engaging the threaded apertures 17. The studs 20 are adapted to project beyond the lapsing surface 15 and engage the surface 11 of the lower lapsing member 10, thereby supporting the upper lapsing member so that its lapsing surface 15 is spaced a distance from the lower lapsing surface 11 equal to the length of the

2

portion of the stud projecting from said surface 15.

Retaining plates or members 24 are secured to the sides of the upper lapsing member 14 by screws 25, which pass through enlarged apertures 26 therein. The retaining plates extend downwardly beyond the lower surface 15 of the member 14 and extend across the length and width thereof to form a retaining well or rim around the lower edge of the member 14, which rim is spaced from the lower lapsing surface 11 to provide clearance sufficient to permit the lapsing of the work. This rim serves to retain the parts being lapsing between the lapsing surfaces. An aperture 27 is provided in the upper lapsing member 14 for the reception of one end of a crank 28 of a suitable rotary device for imparting a rotary motion to the lapsing member 14 or, if desired, the lapsing member 14 may be operated manually.

In the operation of the lapsing apparatus, all the studs 20 are accurately adjusted so that the projecting ends extend out from the lapsing surface 15 a distance equal to or slightly in excess of the overall thickness of the part to be lapsing, which may include the thickness of the part plus any deformations or irregularities, such as a slight bow or curvature. The upper lapsing member is removed from the lower lapsing member and the work to be lapsing as, for example, the part 30, is placed thereon and the upper lapsing member 14 is positioned over it. The overall distance between the two parallel lapsing faces 15 and 11 will be equal to or in excess of the vertical dimension from the plate 11 to the uppermost portion of the part 30. The lapsing member 14 may then be moved in a rotary motion, either manually or by connecting it to a driven crank for automatic operation. As the lapsing member 14 moves on the lower lapsing member, it will move relative to the work 30 and when moved far enough, the retaining rim 24 thereon will engage the work 30 and move it relative to the lower member 10. At the same time, the contacting surfaces of the studs 20 will wear away evenly and permit the lapsing member 14 to move downwardly while maintaining its parallel relation to the member 10. As the studs 20 are worn away and the part 30 moves relative to the upper and lower members, the upper lapsing surface 15 will engage the high spots on the upper surface and lap them away and the lower lapsing surface 11 will lap away the high spots on the underneath side of the part 30 without any undue pressure being exerted on the part 30. The lapsing operation is continued until the part has been lapsing to the required dimension. Thus, the lapsing of the part 30 is accomplished with a pressure which is insufficient to cause deforming or flattening of said part dur-

ing the lapping thereof. If desired, two or more parts may be lapped simultaneously.

What is claimed is:

1. A lapping apparatus comprising a stationary lapping member, a movable lapping member, each of said lapping members having a lapping surface thereon, means for moving said movable lapping member in a plane parallel to one of said lapping surfaces and means associated with one of said members and engaging the other member for separating said members a predetermined distance and gradually reducing the distance therebetween as the lapping operation proceeds.

2. A lapping apparatus comprising a stationary lapping member, a movable lapping member, each of said lapping members having a lapping surface thereon, means for moving said movable lapping member in a plane parallel to one of said lapping surfaces means associated with one of said members and engaging the other member for separating said members a predetermined distance and gradually reducing the distance therebetween as the lapping operation proceeds, and means associated with one of said lapping members for confining a work piece within the lapping area of said lapping member and moving it relative to said other member.

3. A lapping apparatus comprising a stationary lapping member having a lapping surface, a movable lapping member having a lapping surface and being movable on the lapping surface of said stationary lapping member during a lapping operation, and a plurality of supports capable of being worn away during the lapping operation projecting from one of said members and engaging the lapping surface of the other member for providing a predetermined varying spacing between said members as said supports are worn away.

4. A lapping apparatus comprising a stationary lapping member having a lapping surface, a movable lapping member having a lapping surface and being movable on the lapping surface of said stationary lapping member during a lapping operation, a plurality of adjustable supports capable of being worn away during the lapping operation projecting from one of said members and engaging the lapping surface of the other member for providing a predetermined varying spacing between said members as said supports are worn away, and means for adjusting the supporting members to initially space said lapping members.

5. A lapping apparatus comprising a stationary lapping member having a lapping surface, a movable lapping member having a lapping surface and being movable on the lapping surface of said stationary lapping member during a lapping operation, a plurality of adjustable supports capable of being worn away during the lapping operation projecting from one of said members and engaging the lapping surface of the other member for providing a predetermined varying spacing between said members as said supports are worn away, means for adjusting the supporting members to fix the initial spacing between said lapping members, and means mounted on one of said lapping members for confining a work piece within the lapping area of said member and for moving said work piece relative to said other member.

6. A lapping apparatus comprising a stationary lapping member having a lapping surface, a movable lapping member movable on said lap-

ping surface of said stationary lapping member during a lapping operation, and a plurality of adjustable supports capable of being worn away during the lapping operation associated with the movable lapping member and engaging the lapping surface of the stationary lapping member for providing a predetermined varying spacing between said members as said supports are worn away.

7. A lapping apparatus comprising a stationary lapping member, a movable lapping member, a plurality of adjustable supports capable of being worn away associated with the movable lapping member and engaging the stationary lapping member for providing a predetermined varying spacing between said members as said supports are worn away, and means mounted on said movable lapping member for confining a work piece within the lapping area of said movable lapping member and for moving said work piece relative to said stationary member.

8. In a lapping apparatus having a lapping plate provided with a lapping surface, a lapping member movable on the lapping surface of the lapping plate during a lapping operation, a plurality of adjustable supporting members capable of being worn away during the lapping operation projecting from said lapping member to engage the lapping surface of the lapping plate and to provide a predetermined varying spacing between said lapping member and said lapping plate as the supporting members are worn away and means for adjusting the position of said supporting members.

9. In a lapping apparatus having a lapping plate provided with a lapping surface, a lapping member movable on the lapping surface of the lapping plate during a lapping operation, a plurality of adjustable supporting members capable of being worn away during the lapping operation projecting from said lapping member to engage the lapping surface of the lapping plate and to provide a predetermined varying spacing between said lapping member and said lapping plate as the supporting members are worn away means for adjusting the position of said supporting members, and a retaining member associated with said lapping member for confining a work piece within the lapping area of said lapping surface.

10. In a lapping apparatus having a lapping plate provided with a lapping surface, a lapping member movable on said lapping surface of said lapping plate during a lapping operation, and a plurality of supporting members capable of being worn away during the lapping operation projecting from said lapping member to engage the lapping surface of said lapping plate and to provide a predetermined varying spacing between said lapping member and said lapping plate as said supporting members are worn away.

11. In a lapping apparatus having a lapping plate provided with a lapping surface, a lapping member movable on said lapping surface of said lapping plate during a lapping operation, and a plurality of adjustable supporting members capable of being worn away during the lapping operation projecting from the lapping member to engage the lapping surface of the lapping plate and to provide a predetermined varying spacing between said lapping member and said lapping plate as the supporting members are worn away
